ADJUSTABLE ERASER

Jakob Gerster-Seiler, Jegenstorf, Bern,
SwitzerlandApplication January 28, 1943, Serial No. 474,870
In Switzerland January 30, 1942

8 Claims. (Cl. 120—38)

1

My invention relates to an eraser and more particularly to a device comprising a tubular holder and a longitudinal tip or stick of rubber or similar erasing material, inserted in said holder and projecting over one end of the holder, said rubber stick being slidable in the axial direction of the holder whereby the projecting length of the rubber can be adjusted and fresh erasing material can be fed after the consumption of the projecting part of the tip.

Objects of my invention are to provide an erasing tip of the kind described which, during the erasing operation, is reliably secured against being shifted into the holder or being turned in the same; to provide for convenient re-adjustment of the projecting rubber end after consumption of the uttermost end of the rubber tip; and to accomplish these results with handy, simple and inexpensive means.

According to my invention, a strip or blade of a material harder than the rubber, preferably of non-oxidizing metal, is inserted between the holder and the rubber stick and serves as an "anchor" for said stick. This anchor strip may have various shapes, two of which are described in the following description and illustrated in the accompanying drawing in which:

Fig. 1 shows an exemplifying embodiment of the invention, the holder and anchor strip being shown in a longitudinal cross-section.

Fig. 2 shows another exemplifying embodiment in the same manner.

Fig. 3 shows a view of the outer surface of the anchor strip used in the embodiment shown in Fig. 2.

Fig. 4 shows a view of the inner surface of the anchor strip used in the embodiment shown in Fig. 1.

Fig. 5 shows a cross-section taken along the line 5—5 in Fig. 1.

Fig. 6 shows a front view of the anchor strip seen from the right side in Fig. 1.

Fig. 7 shows a rear view of the same anchor strip seen from the left side in Fig. 1.

Fig. 8 shows a cross-section taken along the line 8—8 in Fig. 2.

Referring particularly to the embodiment shown in Figs. 1, 4, 5, 6, and 7, numeral 1 indicates a tubular holder having longitudinal indentations or grooves 2. In Fig. 1, the left end of the holder 1 is broken off. This end is immaterial for the invention and may be adapted for holding a pencil.

A rubber stick 3 having the same or a slightly smaller diameter than the inner diameter of the

2

holder 1 is inserted in the other end of the holder 1 so that the outer end of 3 is free to be used for erasing. The length of the stick 3 is sufficient for feeding erasing material to the open when the outer tip of the stock is consumed.

An anchor strip 4 is inserted between the inner surface of the holder 1 and the rubber stick 3. The strip 4 has a width covering a section of the circumference of the stick 3 and a relatively small thickness. The outer surface of the strip 4 is slightly concave so that this surface about fits the inner surface of an indentation 2. The inner surface of the strip 4 is provided with a plurality of depressions 5, the longitudinal cross-section of the strip thereby having a saw-like shape. The individual teeth of this saw-shape have sides relatively long and gradually recessing at the inner side (left side in Fig. 1) and considerably steeper at the front side (right side in Fig. 1). The inner end of the strip 4 terminates in a thin blunt edge 6. The outer end of the strip forms a knob or boss 7 extending to the outer side somewhat over the outer surface of the holder 1. The outer rim of the holder is provided with a recess or incision in which the boss 7 finds place without towering in axial direction over the rim of the holder. This boss acts as a handle for pulling or pushing the strip 4 and as a stop for the inward motion of the same.

A clip or resilient clamp 8 is affixed to the boss 7 and extends over the outer surface of the holder 1, the far end 9 of this clip touching said surface. The clip is not indispensable, a modification without the clip 8 being also operable. But the clip constitutes an improvement insofar as it makes the pulling and pushing of the strip 4 more convenient, contributes to secure the proper position of the strip at the wall of the holder 1 and, at the same time serves as means for carrying the entire device inside or outside of a pocket or the like, the wall of such pocket being clamped between the clip and the holder.

The embodiment shown in Figs. 2, 3 and 8 comprises a holder 11 having a circular wall, a rubber stick 13 similar to the stick 3 in the embodiment described before, and an anchor strip 14 having depressions 15, a thinned end edge 16 and a boss 17, the details 15, 16 and 17 being similar to the details 5, 6 and 7 of the first embodiment. The cross-section of the strip 14 is bordered by two arcs and, thus, has about a ship-like shape. The outer arc fits about the inner wall of the holder 11. The inner arc presses into the rubber stick 13. The clip 8 of the first embodiment is

replaced by a member 18 forming an eye 19. The advantages of these parts are about the same as those of the parts 8 and 9, except that the eye has the additional advantage to provide means for convenient suspension of the entire device.

In order to secure the eraser stick 3 or 13 to the holder, the thin edge 6 or 16 of the anchor strip is introduced between the stick and the inner surface of the holder, and the boss 7 or 17 is pushed inward until the strip reaches the position shown in the drawing. In this position, the uneven surface of the anchor strip engages frictionally the rubber stick and prevents the same from being turned or pushed farther inward. When, due to consumption of erasing material, the projecting part of the stick becomes shorter than desired, the anchor strip together with the rubber stick is pulled outward as far as suitable and, then, the anchor strip is pushed back again to the original position.

I desire it understood that my invention is not confined to the particular forms described, the same being merely illustrative, and may be carried out in other ways without departing from the spirit of the invention.

I claim:

1. An adjustable eraser comprising a tubular holder; a stick of erasing material inserted in one end of said holder; and an anchor strip inserted at one side between the inner surface of said holder and said erasing stick, and frictionally engaging said stick the other sides of said stick touching said holder immediately whereby said stick can maintain its position relative to said holder while said anchor strip is inserted.

2. An adjustable eraser comprising a tubular holder having longitudinal grooves impressed in its wall; a stick of erasing material inserted in one end of said holder; and an anchor strip inserted between the inner surface of said holder and said erasing stick, said anchor strip having an outer surface curved correspondingly to the adjacent part of said grooved wall and having an inner surface frictionally engaging said stick.

3. An adjustable eraser comprising a tubular holder having a recess in the rim of one end; a stick of erasing material inserted in said end of said holder; and an anchor strip inserted be-

tween the inner surface of said holder and said erasing stick, frictionally engaging said stick and having a boss at one end, said boss extending laterally through said recess of said holder.

5. An adjustable eraser comprising a tubular holder; a stick of erasing material inserted in one end of said holder; and an anchor strip inserted at one side between the inner surface of said holder and said erasing stick, and having an uneven surface pressing into said stick the other sides of said stick touching said holder immediately whereby said stick can maintain its position relative to said holder while said anchor strip is inserted.
- 10 15. An adjustable eraser comprising a tubular holder; a stick of erasing material inserted in one end of said holder; and an anchor strip inserted between the inner surface of said holder and said erasing stick, and having an uneven surface pressing into said stick and comprising depressions and projections alternating in longitudinal direction, the sides of said projections which are situated toward the outer end of the rubber stick being steeper than the sides situated 20 toward the inner end of said stick.
- 25 20. An adjustable eraser comprising a tubular holder; a stick of erasing material inserted in one end of said holder; and an anchor strip inserted between the inner surface of said holder and said 30 erasing stick, having an uneven surface pressing into said stick and having an inner end terminating in a thinned edge.

- 35 7. An adjustable eraser according to claim 3, further comprising a clip affixed to said boss and having an end resiliently touching the outer surface of said holder.

8. An adjustable eraser according to claim 3, further comprising an eye connected to said boss and situated over the outer surface of said holder.

40 JAKOB GERSTER-SEILER.
